UNITED STATES PATENT OFFICE.

WILLIAM CONNOLLY AND ALVIN A. SEALY, OF BROOKLYN, NEW YORK.

DESIGN FOR A BADGE.

SPECIFICATION forming part of Design No. 21,885, dated October 11, 1892.

Application filed August 9, 1892. Serial No. 442,617. Term of patent 7 years.

To all whom it may concern:

Be it known that we, WILLIAM CONNOLLY and ALVIN A. SEALY, both of Brooklyn, in the county of Kings and State of New York, have invented and produced a new and original Design for Campaign-Badges, of which the following is a full, clear, and exact description.

The figure is a front elevation of the badge, showing our design.

The leading feature of our design is the representation of the White House and the figures simulating race-horses bearing riders upon their backs and heading for the White

10 is the usual button of the badge, and 11 the body thereof, the body portion comprising arm-like figures, on the upper end of which are formed, respectively, the representation of the White House and the figures simulating race-horses bearing jockeys upon their backs and heading toward the White House. 20

I claim—

The design for a campaign-badge herein shown and described.

WILLIAM CONNOLLY.
ALVIN A. SEALY.
